UNITED STATES PATENT OFFICE

159,976

STORE SERVICE TRUCK

Sylvan N. Goldman, Oklahoma City, Okla.

Application June 16, 1949, Serial No. 3,325

Term of patent 14 years

(Cl. D14—3)

To all whom it may concern:

Be it known that I, Sylvan N. Goldman, a citizen of the United States, residing at Oklahoma City, in the county of Oklahoma, and State of Oklahoma have invented a new, original, and ornamental Design for a Store Service Truck, of which the following is a specification, reference being had to the accompanying drawing, forming part thereof, in which the figure is a perspective view of a store service truck, showing my new design.

I claim:

The ornamental design for a store service truck, as shown.

SYLVAN N. GOLDMAN.
